UNITED STATES PATENT OFFICE.

FRANK C. DE REAMER, OF SCHENECTADY, NEW YORK, ASSIGNOR TO GENERAL ELECTRIC COMPANY, A CORPORATION OF NEW YORK.

ELECTRIC SWITCH.

1,176,660.

Specification of Letters Patent. Patented Mar. 21, 1916.

Application filed June 17, 1914. Serial No. 845,609.

To all whom it may concern:

Be it known that I, FRANK C. DE REAMER, a citizen of the United States, residing at Schenectady, county of Schenectady, State of New York, have invented certain new and useful Improvements in Electric Switches, of which the following is a specification.

My invention relates to electric switches and operating means therefor, and it comprises various novel features of construction and combinations and arrangements of parts that will be set forth by the detailed description of the best embodiment thereof at present known to me, while its scope will be indicated in my claims.

Among the advantages obtainable in connection with the invention are compactness and simplicity of the mechanism; thorough protection thereof by insulation; and convenience in assembling and securing the mechanism in a casing or other inclosing structure. These and other advantages that will hereinafter appear especially adapt the switch for use in the handles of vacuum or suction cleaners, as herein shown; but its utility is not confined to this application.

In the accompanying drawing, Figure 1 is a longitudinal section of a vacuum cleaner handle with a switch therein, on an enlarged scale; Fig. 2 is a plan view of the switch mechanism proper; Fig. 3 is an end view of an insulative lining, partly in section; Figs. 4 and 5 are detail views showing how an internally threaded bushing piece associated with said lining is secured thereto; Fig. 6 is a detail view of certain parts of the switch mechanism as they would appear from beneath; Fig. 7 is an exterior view of the end of the vacuum cleaner handle tilted forward somewhat, showing a modification; and Figs. 8 and 9 are fragmentary detail views illustrating a modification of certain electrical parts and a modified way of mounting and securing them, Fig. 8 being a sectional elevation corresponding to Fig. 1 and Fig. 9 being a reversed plan view with one of the parts in section.

Referring, first, to Figs. 1 and 2, the end portion 1 of the vacuum cleaner handle is shown as in the form of a metal tube which serves as a casing for the switch proper. Within the casing 1 is an insulating lining 2 shown as a piece of insulating fiber bent to cylindrical form, and within this lining 2

is the switch mechanism. The operating parts of this mechanism are mounted on a base piece 3 (of porcelain, bisque, or other insulating material) which is held in place by screws 4, 4 that extend through the wall 60 of the tube 1 and the lining 2 and engage in peripheral holes 5, 5 in the base. As shown in Fig. 3, internally threaded metal pieces 6, 6 of lead, aluminium, brass, or other convenient metal or alloy are expanded or otherwise secured diametrically opposite in holes in the wall of the lining 2, and the threaded engagement of the screws 4, 4 is in these pieces. These pieces 6, 6 extend inward within the lining 2 and engage in upwardly open peripheral recesses 7, 7 in the insulating base 3 at the bottom of which are the holes 5, 5, thus helping to keep the parts in place and aiding their assembly in the factory. As shown in Figs. 3, 4 and 5, each 75 of these bushing pieces 6 has a reduced portion 8 at one side which fits in the hole in the lining and is expanded at its edge so as to fill a countersink at the edge of the hole. When each bushing piece 6 is stamped or 80 struck up or otherwise formed, slight ridges or projections 9, 9 are formed on the shoulder at the base of the reduced portion 8, and these ridges engage in notches at opposite sides of the hole in the lining 2 and so prevent the bushing from turning therein.

Referring to Figs. 1, 2 and 4, it will be seen that the switch mechanism is mounted on the upper side of the base 3 and is operated by a rotary member 10 extending 90 lengthwise of the tubular casing 1. The mechanism shown is in the main that of the quarter turn rotary snap switch illustrated in my Patent No. 1,022,536, granted April 9, 1912, so that no description is necessary 95 except as to certain special features. As regards the parts directly involved in the snap action, it will be seen that the cam 11 by which the catch-plate 12 is reciprocated in the guide-plate 13 that carries the conductive 100 switch member 14 differs from that shown in my said patent in being merely a circular disk eccentrically mounted, and that the opening in the catch-plate 12 differs correspondingly in being a mere round ended 105 transverse slot. As to the switch member 14 itself, it will be seen that the insulating attachment means 15, 15 by which it is secured to the guide-plate 13 are about 45° from its active end portions, so that in neither its 110

on nor its off position do the lug portions of said member containing said attachment means 15, 15 stand directly opposite the stationary contacts 16, 16. This is of moment 5 in view of the small clearance between the stationary contacts 16, 16 and the lug portions of the switch member in which the parts 15, 15 are secured.

As regards the stationary contacts 16, 16 10 themselves, it will be seen that they are flat metal pieces whose outer ends extend through slots in the upper ends of diametrically opposite metal strips 17, 17 and are headed over. These strips 17, 17 are secured 15 on the periphery of the base 3 and extend from its upper to its lower side in peripheral grooves, and their lower ends are bent inward and provided with screws for the attachment of the current conductors of the 20 vacuum cleaner motor circuit. Each of the strips 17, 17 has a foot 18 that rests against the lower side of the base 3 and is secured by two screws 19, 19 extending down from recesses in the upper side of the base that 25 contain their heads. This mode of mounting and securing the contacts 16, 16 affords perfect insulation and allows the base 3 to be made as small as the operating parts of the switch mechanism will permit.

Referring, now, exclusively to Fig. 1, it 30 will be seen that the rotary operating member 10 is actuated by a rotary device 20 at the end of the handle 1. This device 20 has the form of a cap that fits over and 35 closes the otherwise open end of the handle or casing 1, and in the present instance it is connected to the switch operating member or spindle 10 in such a way that it can yield and move lengthwise of the handle 1 a limited 40 distance. As shown, the connection comprises an internally threaded part 21 screwed on the end of the spindle 10, a yoke 22 secured to the cap 20 and engaging the part 21 in such a way that it may move lengthwise thereof but compels said part 21 to turn with it, and a helical compression spring 23 acting between a squared head 24 at the upper end of the part 21 and a washer 25 loose on said part 21 in the lower end of 50 the yoke 22. The yoke 22 fits in another yoke 26 secured thereto at its upper end by a rivet 27 and the yoke 26 has lugs 28 that are riveted to the top portion of the cap 20 at 29 (see also Fig. 7). This construction 55 allows the switch base 3 to be secured a little lower in the tube 1 than shown, so as to insure that when the part 21 is screwed on the operating member 10 the end of the tube 1 shall come 60 against the bottom of the cap 20 and save the switch from injury by any accidental blow on said cap. This feature also insures against excessively tight jamming of the part 21 on the threaded end of the member 10.

In Fig. 7 I have shown how the yielding connection between the cap 20 and the switch-operating member 10 can be utilized in locking the switch against accidental shutting off when the vacuum cleaner is in use. As here shown, the cap 20 is deeper than shown in Fig. 1 by about the diameter of the heads of the screws 4. Diametrically opposite in the lower edge of the cap 20 are notches 30 (see Fig. 7) that accommodate 75 and engage the heads of the screws 4, 4 when the switch is in the on position and so lock it against accidental turning; while at other times the smooth edge of the cap 20 engages the heads of said screws 4, 4 and the cap is free to turn.

In Figs. 8 and 9 I have shown a modification of the stationary contacts and contact strips and also a different way of securing them to the base 3. As here shown, the contacts proper at 34 are formed by bending over the ends of metal strips 35, and the feet 36 are merely intermediate enlarged portions of said strips. Though these feet 36 are provided with holes for the screws 38, yet as shown the strips 35 are not secured to the base 3 by means of such screws, but by other screws 37 that extend through the portions of the strips 35 in the peripheral grooves in said base 3 and engage nuts 39 in recesses 38 in the base, these recesses being so shaped as to prevent the nuts 38 from turning.

What I claim as new and desire to secure by Letters Patent of the United States, is,— 100

1. The combination of an open ended handle with an external projection near one end, a switch in said handle having a rotary operating member, a rotatable cap over the end of said handle connected to said member to operate the same and having its lower edge notched for interlocking engagement with said projection, said cap being movable lengthwise of said handle to withdraw its edge from engagement with said projection, 110 and means yieldingly urging said cap against said projection.

2. The combination with a switch casing, of an insulative lining therefor having internally threaded metal pieces secured in its wall, 115 an insulating switch base within said lining, and screws extending through the walls of said casing and said metal pieces and engaging said base so as to secure said lining and said base in said casing.

3. The combination of a cylindrical switch casing of uniform diameter, an insulating switch base peripherally fitting the interior of said casing, a rotary switch member mounted at one side of said base and having laterally acting resilient contact portions perpendicular to its axis of revolution, and metal strips in said casing secured on the periphery of said base and carrying inwardly extending contacts for laterally en- 125 130

gaging the contact portions of said switch member.

4. The combination of an insulating switch base having peripheral grooves and laterally open recesses adjacent said grooves; a rotary switch member mounted at one side of said base; metal strips in said grooves extending from one side of said base to the other and each having at one end a contact 5 for engaging said rotary switch member and at the other means for the attachment of a

current conductor; nuts engaged in said recesses so as to be prevented from turning; and screws extending through said strips into said nuts, so as to secure said strips in 15 said grooves.

In witness whereof, I have hereunto set my hand this 16th day of June, 1914.

FRANK C. DE REAMER.
